V. G. APPLE

TOOL FOR FORMING INSULATORS

Filed April 4, 1921

Inventor:
Vincent G. Apple
By James Rain Kunkle
Attest.

UNITED STATES PATENT OFFICE.

VINCENT G. APPLE, OF DAYTON, OHIO.

TOOL FOR FORMING INSULATORS.

Application filed April 4, 1921. Serial No. 458,590.

To all whom it may concern:

Be it known that I, VINCENT G. APPLE, a citizen of the United States, residing at Dayton, in the county of Montgomery and 5 State of Ohio, have invented certain new and useful Improvements in Tools for Forming Insulators, of which the following is a specification.

The invention relates to tools for forming insulators.

One of the objects of the invention is to provide a tool for forming insulators of insulating sheet material and for inserting them in armature core perforations or slots.

Other, further and more particular objects of the invention will become readily apparent, to persons skilled in the art, from a consideration of the following description when taken in conjunction with the drawings, wherein:—

Fig. 1 is an isometric perspective view of the tool and a sheet of insulating material inserted therein.

Fig. 2 is a similar view showing the insulator formed on the tool. Fig. 3 is a sectional view of the tool.

Fig. 4 is a fragment of an end of an armature core showing two of the insulators in slots.

In all the views the same reference characters are employed to indicate similar parts.

The insulator is intended for use in insulating bar wound armatures in which two 35 bar conductors are to be contained within each slot or perforation of the core.

The tool not only forms the insulators but also serves as a convenient means for inserting the insulators within the slots while 40 the formed sheet is still on the tool.

The tool consists preferably of a single piece of steel having a shank 5 and handle 6. There is a shoulder 7 at the junction of the handle and shank to serve a useful 45 purpose. The shank has a slot 8 extending its full length into which to insert one

edge of a sheet of insulating material 9, as at 10, in Fig. 1. The depth of the slot 8 should equal the width of the opening in the armature core. The tool is now rotated 50 with the right hand while the left hand of the operator presses the sheet 8 into contact with the shank of the tool.

The end view of the insulator then formed is indicated in Fig. 4 showing two 55 separated openings 11 and 12, one for each bar conductor that are to occupy the respective slots or perforations in the core of the armature.

After the insulator has been formed in the 60 manner described, and while yet on the tool, it is inserted in the opening in the armature core.

The shoulder 7 prevents the insulator from moving axially on the tool while it is 65 being inserted in the core.

After the insulator has been placed in the core the tool is withdrawn and another insulator is formed and inserted in like manner.

The insulator as an article of manufacture is disclosed and claimed in my Patent No. 1,284,552, dated November 12, 1918.

Having described my invention what I claim as new and desire to secure by Letters Patent, is:—

1. A tool for forming and inserting armature insulators made of sheet material, comprising a shank and a handle with a shoulder at the junction of the members, said shank 80 being transversely slotted to receive the edge of the sheet.

2. A tool for forming and inserting armature insulators made of sheet material, comprising a shank slotted longitudinally and 85 at an angle to its transverse diameter to receive one edge of the sheet and a shoulder near the inner end of the slot.

In testimony whereof I hereunto subscribed my name.

VINCENT G. APPLE.
